TOW GLIDER RELEASE

Norman D. Ashwood, Victoria, British Columbia, Canada

Application August 23, 1949, Serial No. 111,865

4 Claims. (Cl. 244—3)

1

This invention relates to a mechanism incorporated in a glider for releasing the glider.

An object of the invention is the provision of mechanisms in gliders for releasing the gliders automatically and in succession at prescribed intervals, the releasing mechanism having as its principal elements, a long bolt threaded into a nut fixed against rotation in the body of the glider and a vane or propeller secured to one end of the bolt and normally held against rotation by a pin which is held in an operation by a towline attached to the glider and pulling a load, slack in the towline causing the release of the pin.

Another object of the invention is the provision of a mechanism in a glider being towed by a plane for releasing the glider automatically when a bolt threaded into a nut fixed in the body of the glider is reversely rotated by vanes or a propeller operated by air currents when the glider is drawn through the air, a reciprocating rod retaining the vanes or propeller normally against rotation until withdrawn by a lever which is rocked by the action of a spring when the pull on the spring is relaxed.

A further object of the invention is the provision of a mechanism for releasing a glider from a towing plane when a slack occurs in a towline connected between the first glider and a second glider, the mechanism in the second glider releasing said glider in advance of the first glider, variations in the mechanisms in a series of gliders causing the gliders to be released at different intervals of time.

This invention is best understood from a consideration of the following detailed description taken in conjunction with the accompanying drawings, forming part of the specification, nevertheless, it must be borne in mind that the invention is not confined to the disclosure but is susceptible of such changes and modifications as shall define no material departure from the salient features of the invention expressed in the appended claims.

In the drawings:

Figure 1 is a longitudinal side view of a towing plane and a pair of gliders connected together by my improved releasing towline;

Figure 2 is an enlarged longitudinal vertical section taken through the longitudinal axis of a glider;

Figure 3 is a greatly enlarged longitudinal vertical section of the releasing mechanism in a glider, taken along the line 3—3 of Figure 4;

Figure 4 is a transverse vertical section of the

2

releasing mechanism taken along the line 4—4 of Figure 3;

Figure 5 is a greatly enlarged longitudinal vertical section of a cushioning device incorporated in the towline; and

Figure 6 is a fragmentary vertical section of the tail of the towing plane showing the connections for the towline.

Referring more particularly to the drawings, 10 designates a towing plane to which are connected two or more gliders 11 and 12 by means of towlines 13 and 14. The towlines are identical in construction. When the line 13 is released from the glider 11 it is carried by the plane 10. When 15 the line 14 is released from the glider 12 it is carried by the glider 11.

Each towline includes as its main element a long flexible wire or nylon cord 15 with a ring 16 or 17 at each end. A cushioning device 18 (Figures 1 and 5) is incorporated in the center of the wire or cord 15. The ring 16 has an integral wire or shank 20 connected with a swivel 21. A wire 22 (Figures 1, 2 and 6) connects the swivel with an eye 23 which in turn is received by a safety hook 24 on the plane 10. It will be noted from Figures 1 and 2 that the opposite ends of the towlines are substantially identical in construction and therefore the same reference numerals have been applied to like elements.

As shown in Figure 6, an attaching wire or rod 25 extends from and supports the safety hook 24. This wire is carried through a guiding tube 26 having a flange 27 for securing the tube in position on the towing plane 10. The inner end of the wire 25 is attached to a brace bar or partition 28 in the plane.

The safety catch 24a on the towline 14 is secured to a stiff wire or thin rod 30 (Figure 2) which enters a bearing opening in the outer end of a cylinder 31. A piston 32 is rigid with the inner end of the rod 30. A flange 33 is secured to or formed integrally with the inner end of the cylinder and the periphery of said flange is connected at 34 to the inner surface of the tail of 45 the glider 11. The tail of the glider 12 is similarly equipped so that a third glider may be attached to the glider 12 if desired.

A machine screw or bolt 35 is threaded onto a nut 36 (Figures 3 and 4) which has a knurled or rough outer surface fitted frictionally into aligned passage in the abutting ends of sections 37 and 38 of a body formed of some light material, such as a well known plastic, aluminum or Plexiglas. A shell 40 neatly receives the sections and a screw 50 or bolt 41 may be threaded through a boss 42

secured to the shell may be employed for fixing the section 37 more firmly to said shell. The front end of the section 37 and the shell are tapered. Flanges 43 fasten the shell to the inner walls of the fuselage of the gliders. A plug 45 threaded into the rear end of the shell closes said end. A sleeve 46 formed integrally with or secured to the bottom of said shell forms a guide for a rod 47. The longitudinal centers of the sections are cored as shown at 48 and 49 to provide passages for the free longitudinal movement of the screw 35 as will be explained presently.

Vanes or a propeller 50 (Figure 3) has a hub provided with a threaded horizontal passage to receive the screw 35. The outer end of the hub abuts a head 51 on the screw. A shank 52 projecting outwardly from the head has an eye 53 received by the eye 23 on the outer edge of the towline. The rear of the vanes are so arranged that they will be spaced from tapered end of the shell 40. It will be noted that the free end of the rod 47 will project into the path of the vanes and will retain the same against rotation until said rod is withdrawn. When a propeller is employed, it will be necessary to shorten the tapered end of the section 37. A nut 54 fixes the vanes rigidly on the screw 35.

An operating mechanism for the rod 47 is illustrated in Figures 2 and 3. The nut 45 carries a pair of parallel ears 55 projecting rearwardly therefrom. An axle 56 is mounted in the free ends of the ears and a lever 57 is rockable on said axle. A link 58 has one end pivoted at 59 on the lower end of the lever. The other end of said link has pivotal connections at 60 with the rear end of the stop rod 47. The link compensates for oscillating movements of the lever. A stiff wire has one end attached pivotally to the upper end of the lever 57. An angular portion 62 of the wire locates the main portion of the wire along the longitudinal axis of the glider so that portion may be secured to the piston 32 which is acted on by a spring 63 in the cylinder 31.

The cushioning means 18 is illustrated more particularly in Figure 5 and it includes a cylinder 65 closed at both ends. One end has a removable cap 66 so that pistons 67 and 68 may be inserted into said cylinder together with the respective springs 69 and 70. A rod 71 is secured to the piston 67 and after passing through an opening in cap 66 terminates in an eye 72 to which one section of the cord 15 is bound. A rod 73 is rigid with the piston 68 and terminates in an eye 74 located exteriorly of the other end of the cylinder. The rod protrudes through an opening in the adjacent end of the cylinder. The cushioning device eases the strain on the towlines and gliders during a take-off and when the plane and gliders are catapulted.

The operation of my device is as follows:

After the plane 10 is in the air towing the gliders and it is desired to release the gliders, the speed of the plane is reduced whence the towline will become slack. During normal pulling of the gliders, the wires 61 will remain taut against the tension of the spring 63 (Figure 2) and the free end of the rod 47 (Figure 3) will remain in the path of the vanes 50. As soon as tension is released on the wires 61 the springs 63 will rock the levers 57 and withdraw the rods 47 so that the air currents will cause the vanes to rotate.

The screws 35 are rotated by the vanes in such a manner that they will be released from the nuts 36 and the gliders will be free of the plane

10. The screws in the gliders 11 and 12 may have different lengths so that the gliders may be released successively.

5 The gliders may be released for testing the same to determine the defects. Again the gliders may be released for testing the same for defects, as well as being employed for target practice.

10 The swivel 21 in the towlines are important elements during the release of the gliders. Since the screws 35 are rotated by the vanes 50 to turn said screws out of the nuts 36 there would be a tendency to twist the towlines. However, the swivels permit the eyes 53 to turn the eyes 23 but such rotation is not transmitted beyond said swivels.

15 Any number of gliders may be towed. However, the last glider in the series will be released first because the vanes will start rotating as soon as the gliders are in flight. This is due to the fact that no pull is exerted on the safety catch 24a and the rod 47 will be out of engagement with the vanes 50 since the spring 63 will have forced the wire 61 inwardly to rock the lever to the dotted line position shown in Figure 2. It must be borne in mind that the slack in the towlines has no effect on the last glider in the series since no pull is exerted on the safety catch 24a projecting from the tail of said glider.

20 It should be understood that the pitch of the threads of the bolt 35 may be varied to increase or decrease the time at which a glider is released or a variance in the angle of the propeller blades will obtain the same effect.

25 What I claim:

30 1. A releasable mechanism incorporated in a glider comprising a nut fixed against rotation in the body of the glider, a screw threaded into the nut in one direction in the nut, one end of the screw projecting beyond the nose of the glider, 35 vanes secured to the projecting end of the screw, a rod having an end extending into the path of the vanes for retaining said vanes against rotation, a lever rockably mounted in the glider and having pivotal connections with the rod, a spring 40 in the tail of the glider, means acted on by the spring and connected with the lever for rocking the lever in an operative direction to release the rod from the vanes, the spring being retained in an inoperative position by a releasable load to prevent rocking of the lever until the load is released, the released vanes rotating the screw when the glider is soaring through the air to turn the screw out of the nut and a flexible towline connecting the glider to a towing plane.

45 2. A releasable mechanism incorporated in a glider comprising a nut fixed against rotation in the body of the glider, a screw threaded into the nut in one direction in the nut, one end of the screw projecting beyond the nose of the glider, 50 vanes secured to the projecting end of the screw, a rod having an end extending into the path of the vanes for retaining said vanes against rotation, a coil spring tending to release the rod from the vanes, means causing compression of the spring to prevent release of the rod and including a towline attached at one end to said means, the other end of said line being connected to a load, slack in the towline relieving compression of the spring, the released vanes rotating the screw in a direction to withdraw the screw from the nut.

55 3. A releasable mechanism incorporated in a glider comprising a nut fixed against rotation in the body of the glider, a screw threaded into the nut in one direction in the nut, one end of the screw projecting beyond the nose of the glider, 60 a rod having an end extending into the path of the vanes for retaining said vanes against rotation, a coil spring tending to release the rod from the vanes, means causing compression of the spring to prevent release of the rod and including a towline attached at one end to said means, the other end of said line being connected to a load, slack in the towline relieving compression of the spring, the released vanes rotating the screw in a direction to withdraw the screw from the nut.

65 4. A releasable mechanism incorporated in a glider comprising a nut fixed against rotation in the body of the glider, a screw threaded into the nut in one direction in the nut, one end of the screw projecting beyond the nose of the glider,

vanes secured to the projecting end of the screw, a rod having an end extending into the path of the vanes for retaining said vanes against rotation, a towline connecting the projecting end of the screw with a towing plane, a spring normally urging the rod to release the vanes to rotate the screw for withdrawing the screw from the nut, a towline connected between the spring and a load to prevent the spring from withdrawing the rod from the vanes, a slack in the last mentioned towline releasing the spring for withdrawing the rod.

4. A releasable mechanism incorporated in a glider comprising a nut fixed against rotation in the body of the glider, a screw threaded into the nut in one direction in the nut, one end of the 15

5 screw projecting beyond the nose of the glider, vanes secured to the projecting end of the screw, a rod having an end extending into the path of the vanes for retaining said vanes against rotation, a spring urging the rod towards release, a flexible means connected between the spring and a load extending rearwardly from the tail of the glider for retaining the spring against movement, a slack in the flexible means releasing the spring 10 to free the rod from the vanes so that the vanes will rotate the screw and withdraw said screw from the nut.
